WOODWORKING MACHINE

Ivan H. Bradley, Stratford, Conn.

Application September 19, 1935, Serial No. 41,196

27 Claims. (Cl. 142—4)

This invention relates to new and useful improvements in woodworking machines and relates particularly to an automatic wood turning machine.

5 An object of the invention is to provide an automatic wood turning machine capable of rapidly turning out a large number of pieces.

Another object of the invention is to provide a machine having the characteristic stated and 10 including a variety of adjustments whereby the machine is capable of turning pieces of widely differing sizes and configurations.

15 Other objects and advantages will become apparent from a consideration of the following detailed description taken in connection with the accompanying drawings wherein a satisfactory embodiment of the invention is shown. However, it will be understood that the invention is not limited to the details disclosed but includes all 20 such variations and modifications as fall within the spirit of the invention and the scope of the appended claims.

In the drawings:

Fig. 1 is a side elevational view of the improved machine, certain parts being omitted for the better showing of other parts;

25 Fig. 2 is a view looking into the power or head end of the machine, gear casings and the like being broken away;

Fig. 3 is a view similar to Fig. 2 but taken looking into the opposite end of the machine;

30 Fig. 4 is a plan view of the machine, parts being broken away in order that details of construction may be shown;

Fig. 5 is an elevational view of a chute together 35 with its supporting parts;

Fig. 6 is a detail sectional view showing the mounting of a pair of cam posts and also showing the cams and a pair of work holding chucks;

40 Fig. 7 is a detail elevational view showing the mounting of the head and tail stocks at one side of the machine;

Fig. 8 is a detail sectional view taken substantially along the line 8—8 of Fig. 7;

45 Fig. 9 is a top plan view of an adjustable member on which the head and tail stocks of the machine are mounted;

Fig. 10 is a top plan view of one of the chutes of the machine;

50 Fig. 11 is a side elevational view of a clutch employed; and

Fig. 12 is a view of the clutch with the cover removed.

Referring in detail to the drawings, the machine includes a base 10 carrying an upright

central supporting member 11 which at its upper end includes a table portion 12 mounting spaced brackets 13 and 14. Each bracket comprises a base portion secured to the table 12 by bolts 15 and further includes a bearing portion 16 which bearing portions mount a central shaft 17 carrying a rotary cutter generally designated 18, the construction of which varies depending on the work to be performed. From this it will be understood that the particular construction of 10 the cutter forms no part of the present application.

At the head end of the machine the upright 11 is provided with outwardly and upwardly extending webs 19 supporting a portion 20 in the nature of an extension of the table 12 and secured to such extension is a frame or casting 21 on the upper side of which is mounted an electric motor 22. Within the frame 21 there is arranged a bracket member 23 held in place by 20 bolts 24 and carrying a bearing 25 through which the shaft 17 extends. The shaft 22a of motor 22 carries a multiple pulley 26 over which are trained belts 27 also trained about a corresponding pulley 28 on the shaft 17, such pulley 28 25 being arranged on said shaft between the brackets 13 and 23.

On the shaft 17 outwardly of the bearing 25 there is arranged a sprocket 29 (see Fig. 2) over which is trained a chain 30 also trained about 30 a relatively large sprocket wheel 31 on a shaft 32 carrying a worm 33. Such shaft 32 is mounted in bearings 34 carried by a bracket 35 which latter includes a base portion 36, mounted on the machine base 10, and a pair of spaced upright 35 arms 37 carrying the bearing portions 34 (Figs. 1 and 2). Mounted on the bracket base portion 36 are a pair of spaced bearing members 38 and 39 secured in place as by bolts 40 and each including an upwardly projecting guide lug 41, the 40 purpose of which will later appear.

Bearing members 38 and 39 rotatably mount a shaft 42 and secured on such shaft between the adjacent portions of said bearing members is a worm wheel 43 meshing with the worm 33 on the 45 shaft 32. It will, thus, be seen that the motor 22 in addition to driving the cutter shaft 17 also operates to drive the transversely extending shaft 42. Keyed to shaft 42 for sliding movement therealong are beveled gears 44 and 45 each provided with a collar 46 into which extends a yoke member 47. Said yoke members are secured to a rod 48 slidable through the guide lugs 41 previously mentioned and to this rod is secured a collar 49.

Secured on base 10 by bolts 50 is an arm or bracket 51 to which the lower end of a hand lever 52 is pivotally attached as at 53. A link 54 has one end pivotally anchored to the lever 52 intermediate the ends of the latter at 55 and the other end of said link is pivotally connected with the collar 49 as at 56. With this construction it will be apparent that as the lever 52 is swung in one direction or the other about its pivot 53 the rod 48 will have a sliding movement imparted to it in the direction of its length and such movement will, through the yokes 47, be imparted to the collars 46 and thus to the bevelled gears 44 and 45 sliding them in one direction or the other along the shaft 42.

On the portions of the base 10 at each side of the upright 11 there are formed enlargements or lugs 57. Two of these lugs are at each side of the upright 11 and they are arranged in spaced relation as shown best in Fig. 1 and on the upper side of each lug a bearing member 59 is secured as by bolts 59. Supported by such bearing members at the respective sides of the upright 11 are shafts 60 and 61 and each shaft at the head end of the machine carries a bevelled gear 62 and in the rear of such gear sprocket wheels 63 and 64. Motion is transmitted to the shafts 60 and 61 from the motor 22 when the bevelled gears 44 and 45 are shifted along the shaft 42 into mesh with the bevelled gears 62.

Mounted on the respective shafts 60 and 61 for pivotal movement with respect thereto are similar frames 65 and 66 each substantially in the form of an inverted U, and including a front leg 67, a rear leg 68 and an upper connecting portion or bar 69. In addition to the frames 65 and 66 being duplicates of one another the mechanisms on or associated with the respective frames are duplicates of one another so that substantially identical structures are provided at each side of the upright 11 of the machine base. Secured to the front legs 67 as by bolts 70 are brackets 71 each having three step-like portions 72, 73 and 74 provided respectively with holes or recesses 75, 76 and 77.

Also mounted by each front leg 67 is a short eccentric stud or shaft 78 on which intermediate its ends is pivotally mounted a bracket comprising a pair of spaced arms 79 at their inner ends carrying a pin 80 mounting a gear 81 located between the arms. A hand piece 82 is pivotally connected at 83 with the outer ends of the arms 79 and said arms in addition to being rockable about the shaft 78 are also shiftable along said shaft. Each hand piece 82 at 84a pivotally mounts a pawl member 84 including a pin 85 adapted to be engaged in a selected one of the openings 75, 76 and 77 of its associated bracket 71. A small coil spring 86 arranged between the outer end of the pawl 84 and the lever 82 normally tends to rock the pawl in a direction to carry its pin 85 into a selected one of said openings of bracket 71.

On each shaft 78 is a gear 87 arranged between the arms 79 and meshing with the gear 81. Secured on each shaft 78 is a relatively large sprocket wheel 88 over which and the sprocket wheel 64 there is trained an endless chain 89 whereby as the shafts 60 and 61 are being driven the sprocket wheels 88 and the gears 87 of the respective frames 65 and 66 are driven and it will be understood that gears 87 meshing with gears 81 the latter will be driven. About each shaft 78 is an eccentric sleeve 90 mounting sprocket wheel 88 and adapted to be adjusted so as to adjust

said sprocket wheels 88 relative to the sprocket wheels 64 and thus keep the drive chains 89 under the proper tension.

Extending through and mounted for rotary movement by the legs 67 and 68 of each frame 5 is a shaft 91 which at its front end mounts large, intermediate and small gears 92, 93 and 94 all rigid with the shaft and enclosed by a gear casing 95 cut away at its lower inner side as shown in the right hand portion of Fig. 2 whereby a portion of each of said gears is exposed so that a gear 81 may be brought into mesh with the desired one of said gears 92, 93 or 94 as will later more fully appear. Each gear housing 95 is carried by a bracket-like portion 96 (see Fig. 1) secured to the forward leg 67 of the frame as by bolts 97.

The rate of rotation of the shaft 91 depends on which of the gears 92, 93 or 94, the gear 81 is meshing with. By means of the mechanism above described the gear 81 may be brought into mesh with any one of the gears 92, 93 or 94. This is suggested particularly by Fig. 2 wherein at the right hand side of the figure the gear 81 is shown as meshing with the gear 92 while the gear 81 at the left side of the machine is shown as meshing with the gear 94.

To effect the change in speed the pawl member 84 is depressed against the action of its spring 86 and then the hand piece 82 is rocked to shift the arms 79 about the shaft 78 so as to carry the gear 81 into a free position. Next, the hand member is shifted laterally so as to move the gears 81 and 87 and bracket arms 79 laterally into a position opposite or beyond the edge 35 of the gear with which gear 81 is to be meshed. Then on the hand piece being rocked back the gears will be meshed and the pawl 84 is released so as to have its pin 85 enter one of the openings 75, 76 or 77 to lock the parts in their adjusted positions.

It will be understood that when the pin 85 of a pawl member 84 is in the opening 75 the gear 81 controlled by the hand piece mounting such pawl will be in mesh with the large gear 92 on the shaft 91. When that same pawl pin is in the opening 76 the mentioned gear 81 will be meshing with the gear 93 of shaft 91 and when the pawl pin is in the opening 77 the mentioned gear 81 will be in mesh with the gear 94 on the shaft 91. From the above it will be seen that mechanism is provided whereby the shaft 91 may be driven at one of three speeds depending on the manual shifting of the hand piece 82 to change the position of the gear 81.

Fixed to each shaft 91 between the legs 67 and 68 is a sleeve 98 carrying a cam 99 the purpose of which will later be fully described. On each shaft 91 at the outer side of the frame leg 68 is a bucket cam 100 comprising an inner cam member 101 fixed to the shaft and an outer hollow cam member 102 secured to the member 101 as by screws 103 and including side wall portions 104 spaced from the edges of the cam member 101 as shown best in Fig. 3. It is noted that the portion of the member 101 about the shaft 91 projects out of the hollow cam member 102 and that such projecting portion of the cam member 101 has a cut-away or relieved portion 105, the purpose of which will later fully appear. Obviously, as a shaft 91 is rotated its cam 100 will be carried with the shaft.

Fixed to the outer or tail end of the frame upright 11 as by means of bolts 106 is a cross bar 107, the ends of which extend beyond the sides 75

of the upright 11 for a purpose to be described. Also, fixed to the same portion of the machine as by screws 108 is a short bar 109 and it will be noted in Fig. 3 that the bar 109 is spaced below the intermediate portion of the bar 115 and that into said space is inserted the free or inner end portions of brackets 110 each at its outer end carrying a roller 111. Such brackets are each secured in place by a bolt 112 and each bracket is provided with a slot 113 through which its securing bolt extends whereby the brackets may be adjusted in directions to bring their rollers 111 closer to or further from one another.

15 Normally the bolts 112 are tight so that the rollers 111 may turn about their mounting studs but may not be shifted laterally with respect to the upright portion 11 of the machine base. The cams 100 cooperate with the rollers 111 in such manner that the frames 65 and 66 and the parts carried thereby are in alternate order swung inwardly and outwardly moving about the shafts 60 and 61 as pivots or fulcrums. In Fig. 3 the frame 65 is shown as in an inner position 20 while the frame 66 is in an outer position, certain mechanism on the frame 65 in Fig. 3 being positioned to present work to the rotary cutter 18 while the frame 66 is in position for its work spindles to receive a piece to be later presented 25 to the cutter.

30 Disposed on the upper side of the connecting bar 69 of each of the frames 65 and 66 is a member or sub-table 114 shown particularly in Figs. 7, 8 and 9. This member comprises an upper bar 115 and depending lug portions 116 and 117 engaging on the upper surface of the connecting bar 69 so that the bar portion 115 is spaced above the connecting bar 69. Sub-table 114 is pivotally mounted on the connecting bar 69 by a bolt 118 although a ball or other anti-friction bearing 119 is arranged about said bolt between the bar portion 115 and the connecting bar 69. Bolt 118 is tightened in place by a nut 120 and passes through and has either a neat or tight fit in an opening in the connecting bar 69 but passes through an elongated slot 121 in the bar 115.

35 With such an arrangement it will be apparent that on loosening of the nut 120 the sub-table 114 may be adjusted longitudinally to properly position it with respect to the connecting bar 69. Further, in its upper surface and extending for its entire length bar 115 is provided with a groove 122 the purpose of which will later be set forth and adjacent one end is provided with a pair of slots 123 while adjacent its other end is provided with similarly spaced slots 124.

40 Mounted on the bar 115 are the head and tail stocks 125 and 126 respectively of the machine and the head stock in its under side is provided with a rib 127 (see Fig. 2) entering the groove 122 in the upper side of bar 115 and the head stock is secured in place by bolts 128 passing through the slots 123 of said bar. It will be apparent that on loosening of the bolts 128 the head stock may with the limits of the slots 123 be adjusted longitudinally of the bar. Similarly the tail stock 126 is provided with a rib 129 (see Fig. 3) entering the groove in the upper side of the bar 115 and bolts 130 passing through the slots 124 secure the tail stock to the bar. On loosening of these bolts the tail stock may be adjusted longitudinally of the bar.

45 Toward its outer end each bar 115 is provided 50 with an opening 131 into which extends a stud

or pin 132 carried by and projecting upwardly from the connecting bar 69 of the frame member mounting said bar. Threaded openings 133 lead from opposite edges of the bar 115 into said opening 131 and set screws 134 threaded through said openings engage opposite sides of the stud 132 so as to lock the sub-table 114 and parts carried thereby against turning movement about the bolt 118 and relative to the connecting bar 69.

55 Obviously, on slackening off on one of the set screws 134 and tightening of the other set screw the sub-table 114 will be adjusted about the bolt 118 so as to swing the head stock inwardly and the tail stock outwardly, or vice versa depending on the manner in which the screws are adjusted so that a piece of work held between the head and tail stock spindles will be presented to the rotary cutter at an angle whereby more material will be cut from one end portion of the piece than from the other end portion thereof. This adjustment is, of course, used only in cases where the work is to be cut or have more material removed at one end than at the other.

60 It will be understood that there is a head stock and tail stock carried by each of the frames 65 and 66. The head stock includes a base portion 135 into which the securing screws 128 enter and a bearing portion 136 through which extends a hollow shaft or spindle 137 at its forward end carrying a chuck 138 to engage the work as will later be described. Also included with each head stock is a gear casing 138a through which the shaft 137 extends as shown in Fig. 1.

65 Each tail stock includes a base portion 139 carrying a pair of spaced front and rear uprights 140 which at their upper ends carry bearing portions 141 and 142. A gear casing 143 also forms part of the tail stock and extending through such gear casing and through the bearings 141 and 142 is a shaft or work spindle 144 which at its forward or inner end carries a toothed chuck 145 for engagement with the work. Such chuck includes a shank 145a entering the hollow work spindle 144.

70 A shaft 146 extends through the base portions of both the head and tail stocks and through the gear casings 138a and 143 and at the inner side of the gear casing 138a an automatic clutch 147 is mounted on said shaft. Connected to drive said clutch is a sprocket wheel 148. Trained over such sprocket wheel and the sprocket wheel 63 on the shaft 60 at one side of the machine and the shaft 61 at the other side of the machine is an endless chain 149 whereby the shaft 146 at each side of the machine is driven. Within each gear casing 138a a gear 150 on the shaft 146 meshes with a gear 151 on the shaft or work spindle 137 of the head stock and within each gear casing 143 a gear 152 on the shaft 146 meshes with a gear 153 on the shaft or work spindle 144 of the tail stock. With this arrangement the shafts of both the head and tail stocks are each driven directly from the shaft 146 and therefore any back-lash in the gears will be in the same direction for all the parts and both the head and tail stock work spindles will be driven with the same constant motion.

75 At each side of the machine there is arranged a work feeding chute and while such chutes are of identical construction and in detail will be described in the singular they are generally designated 154 and 155 respectively. For the mount-

ing of the chute a pair of arms 156 extend laterally from each side of the vertical portion 11 of the machine base and such arms 156 are by means of bolts 157 secured to mounting lugs 158 which are preferably cast with the machine base. At its outer end each arm is provided with a head-like portion 159 having vertically extending groove or depression therethrough and vertically disposed legs 160 have their lower end portions 10 secured to said heads 159.

Legs 160 are secured to the head portions of the arms 156 by bolts 161 passing through vertically extending slots 162 of the legs and it will therefore be apparent that on loosening of the 15 bolts 161 the legs 160 may be adjusted vertically. Since the legs are partially received and have a neat fit in grooves in the head portions 159 of the arms 156 it will be apparent that the legs have no lateral movement. At their upper ends 20 the legs 160 are secured to angle brackets 163 by means of bolts 164 and it is noted that the lower edge portion 165 of each of said brackets is arcuate or curved, the center of its radius being the center of its securing bolt 164.

25 Secured to the upper side of the top wall or angle portion of the pair of angle brackets 163 at each side of the machine is a mounting plate 166 and it is noted that such plate spans the pair of angle brackets and is secured to them by flat 30 headed machine screws 167a. Arranged in spaced relation and disposed on the upper side of the plate 166 are a pair of angle members 168 each including a base portion 169 arranged against the upper side of the plate and having a 35 depending rib 170 entering a groove 171 in the upper side of the plate and through the base portions 169 of the angle members bolts 167 extend and secure the members 168 in place. In its base portion each of the members 168 is provided with a slot 172 through which its bolt 167 extends whereby on loosening of the bolts 167 the members 168 may within the limits of the slots 172 be adjusted toward or from one another.

Each of the angle members 168 clamps in place 45 and has secured to it a chute side plate 173, each such plate including an extension 174 of reduced height and passing under a lip-like portion 175 at the upper edge of the vertical portion of one of the members 168. The arrangement is such 50 that the lips 175 engage over the upper edges of the extensions 174 of chute side plates and on tightening of the bolts 167 to secure the members 168 of the plate the said extensions of the chute side plates are clamped against the plate 166. 55 The side plates of the chutes are additionally secured in place by means of bolts 176 passing through slots 177 in the extensions 174 and through or into the vertical portions of the members 168 whereby the extensions of the side plates 60 are clamped laterally against the vertical portions of said members 168.

Disposed at the inner side of one chute side plate 173 is a pair of vertically extending angle bars 178 and 179 while at the inner side of the 65 other side plate of the same chute there is arranged a pair of vertically extending angle bars 180 and 181. As shown, the machine is set up and adjusted for the automatic turning of paint brush handles although it is to be understood 70 that the machine is not limited to use for that particular purpose but is capable of a wide variety of uses depending on the making of various adjustments and on the type and construction of cutter and cams used all as will later more fully 75 appear. Before being presented to the machine

the work or blanks are roughly shaped and in the drawings the work or blanks to be turned are designated 182 and each blank includes a head-like portion 183 and a handle or grip portion 184. (See Fig. 10.)

5 The vertical angle bar 178 is secured in place by bolts 185 passing through vertically extending slots 186 in a chute side plate 172 while the vertical angle member 179 is secured in place by bolts 187 passing through horizontal slots 188 in the 10 same chute side plate. Obviously, the angle bar 179 may be adjusted toward the angle bar 178 and in the present case such adjustment is made so as to have the inwardly directed flanges of such bars spaced apart a distance equal to the 15 length of the head portion 183 of one of the blanks 182. This is as clearly shown at the left hand side of the machine in Fig. 4 and also in Fig. 10.

The angle bar 181 is secured in place by bolts 189 extending through vertical slots 190 in the 20 other side plate of the chute while the angle bar 180 is secured in place by bolts 191 passing through horizontal slots 192 in the said other side plate of the chute. Obviously, on loosening of the bolts 191 the bar 180 may be adjusted 25 toward the bar 181 and as here shown this adjustment is made so as to have the inwardly directed flanges of said bars spaced apart a distance equal to the width of the outer or free end portion of the shank or handle 194 of the blank 182.

30 In addition to the bars 179 and 181 being adjustable toward the bars 178 and 180 the side plates 173 of the chutes are also adjustable horizontally inwardly and outwardly with respect to the cutter shaft 17. This last is accomplished by 35 loosening of the bolts 176 after which the side plates 173 may be shifted inwardly and outwardly within the limits of the slots 177. The chute side plates are also adjustable toward and from one another since on loosening of the bolts 167 the angle members 168 may be shifted toward and from one another within the limits of the slots 172. These slots provide for fine adjustments of the members 168 and for coarser or longer adjustments the bolts 167 are removed and then the 45 members 168 are shifted and the bolts inserted through other holes or openings in the plate 166. In this connection it will be particularly noted in Figs. 4 and 5 that such plate adjacent its ends is provided with series of openings 193 into which 50 the bolts 167 may be selectively inserted.

A pair of finger-like members 194 are arranged to close the lower end of each chute and before the machine is started each chute is loaded with the pieces 192. Such pieces are 55 arranged with their head portions 183 between the inwardly directed flanges of the angle bars 178 and 179 and with the ends of their shank portions 194 between the inwardly directed flanges of the angle bars 180 and 181. The lowermost 60 piece 192 rests on the members 194 which are spaced apart as best shown in Fig. 1. It will be understood that the various parts have been adjusted so that the side plates 173 of the chutes are properly related and spaced as are the 65 various angle bars carried by such side plates.

The angle bars 179 and 181 are so adjusted 70 vertically that their lower ends stop at a point just above the lowermost blank or piece 192 as shown at 195 in Fig. 3, but the angle bars 178 and 180 have their inwardly directed flanges extending down substantially to the upper surface of the members 194 as shown at 196. The angle bars together with the members 194 serve to 75 properly locate the pieces 192, so that the latter

will be automatically removed one at a time as will later appear.

Means are provided for assisting in accurately locating the lowermost piece 182 in the chute and, of course, one such means is associated with each chute. The mentioned means includes a bracket 197, one arm of which is secured against the other side of a chute plate 173 by the lowermost of the bolts 189 while the other arm is secured to the inwardly extending flange of the angle bar 181 as by a bolt or screw 198. It will, therefore, be clear that the bracket 197 is vertically adjustable with the angle bar 181. Such bracket 197 includes a bearing portion 199 through which extends a shaft 200 to the outer portion of which there is attached a finger 201. To the lower end of this finger one end of a coil spring 203 is anchored while the other end of such spring is anchored to a pin 204 rigid with a side plate 173.

A finger 205 is carried by the inner portion of the shaft 200 and the spring 203 normally acts to maintain the lower inwardly curved portion 206 of said finger against the lowermost of said pieces 182. The end portion 206 of the finger 205 engages an edge of the lowermost piece 182 intermediate the ends thereof and forces such piece laterally or attempts to force the piece laterally so as to insure said piece bearing against the inwardly directed flanges of the angle bars 178 and 180. As the spring so acts it will be apparent that the lowermost piece in the chute has a definite position from which it may be taken as will be described.

Since the chute structure disclosed provides for the adjustments described it will be understood that it is adapted to support and feed various shapes of pieces, it simply being necessary that proper adjustments be made. It may be adjusted to receive pieces of greater or lesser length than those shown or pieces where the widths at the ends are different from those shown or are the same at both ends. Further, by adjusting the side plates inwardly or outwardly the bottom piece in a stack will always occupy the same position with respect to the other parts of the machine and by adjusting only one of the legs 160 up or down the plates 166 will be arranged at an incline so as to properly support pieces which are thicker at one end than at the other. This may be accomplished since the legs are connected with the brackets 163 by a single bolt 164 which on being loosened form pivotal connections and it is noted that the lower edges of the brackets are arcuate at 165 providing for turning of the brackets relative to the legs without binding.

The tapered shank 207 of the chuck 138 is received in the hollow shaft or work spindle 131 of the head stock in the usual manner and on said shaft in the rear of the chuck there is arranged a cam 208 the purpose of which will later appear. In the present disclosure the chuck 138 is elongated and includes upper and lower flanges or flange-like portions 209 spaced apart so as to receive the head portion 183 of a piece 182. Between the flanges 209 the chuck is provided with a projection or tit 210 to dig into the piece to be turned. Since each head stock is adjustable along the bar 115 of its mounting member 114 it will be clear that the chucks 138 at opposite sides of the machine may be aligned even though their tapered shanks 207 are of different lengths or do not enter their respective hollow work spindles to the same extent.

This is also true with respect to the tail stocks and their chucks 145.

The tail stock shaft or work spindle 144 is longitudinally shiftable and secured to it is a collar 211 having a groove receiving a ring 212 to which a yoke 213 is secured as by pins 214. Yoke 213 is rigid with, but off-set from, an arm 215 which is pivoted at 216. At its lower end arm 215 is bifurcated providing portions 217 and 218 to the former of which a roller 219 is secured by a bolt 220. A coil spring 221 has one end anchored to a pin 222 on the bifurcated portion 218 and the other end of said spring is connected at 223 with the lower end of a stationary arm 224 secured to the tail stock as by bolts or screws 225.

The spring 221 constantly tends to rock the arm 215 about the pivot 216 so as to shift the work spindle 144 and the chuck 145 toward the work or toward the left in Fig. 1. As seen in that figure the roller is at the top of the cam 99 so that the spring is elongated and the spindle 144 and the chuck 145 are in retracted positions. It will be recalled that shaft 91 is a driven shaft and from this it will be seen that as the shaft continues to turn cam 99 will be carried away from the roller 219 and the spring 221 will then rock the arm 215 about its pivot to move spindle 144 and chuck 145 toward the work.

When this occurs the chuck 138 is positioned at one end of the lowermost piece 182 of a stack while the chuck 145 is in line with the other end of said piece. As the chuck 145 and its spindle are projected by the spring both chucks have stopped turning by reason of the release of the clutch 147 as will later be explained, and the chuck 145 forcefully strikes the lowermost piece 182 and shifts it longitudinally to carry one of its end portions into the chuck 138 and to partially imbed the teeth of chuck 145 in the piece.

As shaft 91 revolves the bucket cam 100 engages with the roller 111 and rocks frame 65 about shaft 60 as a fulcrum so as to move the work spindles of the head and tail stocks of said frame inwardly of the machine to bring a piece of work held by said spindles into engagement with the rotary cutter 18. At the same time the other bucket cam is cooperating with its roller 111 to rock the frame 66 in the opposite direction so as to position the spindles of its head and tail stock in their outermost position and in alignment with the respective ends of a piece to be taken from a chute as shown in Fig. 3. Bucket cams operate constantly to shift the frames 65 and 66 alternately with respect to one another so that while the spindles of one frame are presenting a piece of work to the cutter the spindles of the other frame are taking a piece of work from a chute.

A bar 226 similar to the bar 107 extends transversely of the machine at the head end thereof and these bars have their outer end portions bent so that the end portions of one bar extend toward the end portions of the other and each end portion of each bar carries a set screw 227 adapted to be adjusted more or less through the bar. These set screws are positioned to be engaged by the respective arms of the frames 65 and 66 when such frames are in their outermost positions and thus form stops limiting the outward movement of the frames. It will be understood that the stop screws 227 are adjusted to extend more or less through the bars 107 and 226 depending on the positions occupied by the frames when their work spindles are taking a piece of work from a chute and this, of course, depends on the shape and

size of the piece to be turned. The rollers 111 which cooperate with bucket cams are mounted on adjustable pieces 110 as previously explained.

Each of the clutches 147 includes a body portion 228 (see Fig. 12) carrying an annular hub 229 receiving the spindle 137 of the head stock. At its outer edge the clutch body 228 is provided with an annular flange 230 about which is sprung a heavy ring 231 split as at 232 (see Fig. 12). A cover 233 fits over the body and the split ring and is secured in place as by a bolt 234 and pivotally mounts the transversely circular reduced portion 235 of a transversely square or rectangular key 236. The key 236 extends into the space between the ends of the ring 231 and to the outer end or on the outer portion of the extension 235 of said key a small lever 237 is secured, one end portion of said lever extending between stops 238 while the other end portion thereof is curved as at 239 and extends beyond the body of the clutch.

Owing to the action of the ring 231 the hub of the clutch is clamped to the work spindle 137 so as to turn the same as the clutch is turned by the sprocket 148 and the arrangement is such that on the lever 239 being rocked or being held against movement while the clutch body moves the key 236 is rocked and a pair of its corners engaging the ends of the split ring 231 the latter is expanded permitting the hub portion of the clutch to also expand and release its grip on the work spindle 137. When this occurs the clutch simply turns on the spindle being driven by the motion transmitted through the sprocket 148 while the spindle itself remains stationary. This clutch comes into play during the time the work spindles are taking a piece from a chute.

An angle bracket 240 secured to the bar 226 as by bolts 241 is positioned to be engaged by the lever 237 of the clutch of the frame 65 at the proper time. The plate 246 is engaged by the 40 convex or outer side of the clutch lever 237 as said lever moves downwardly as best shown in Fig. 2. The lever 237 of the clutch of the mechanism of the frame 65 at the proper time wipes against the under side of a plate 242 forming part 45 of an angle member secured to an arm 243 as by bolts 244. The bolts 244 pass through slots in the angle member 242 while the bolts 241 pass through slots in the member 240, this arrangement being provided for adjustments whereby to 50 have the clutch levers engage the plates at the proper time and remain in engagement with them for the proper length of time. The engaged portion of the bracket or angle member 242 is located above this clutch so that the lever of the 55 clutch of the mechanism of the frame 65 engages and wipes against the under side of the horizontal portion of said member.

A bracket 245 is secured against the upper side of the table 12 as by bolts 246 and such bracket 60 includes a vertical portion to which a cross bar 247 is secured as by bolts 248 passing through slots 249 in the cross bar. Uprights 250 are secured to the cross bar and each at its upper end carries an insert or wear piece 251 formed of hard 65 wear resisting metal. The cams 263 are adapted to work against these wear plates 251 so as to properly position the work with respect to the cutter while a final or finishing cut is being made.

In the operation, assuming that the proper cams 70 are in place and that all necessary adjustments have been made to have the machine operate on a particular piece, as for example, the piece 132 of the drawings, both chutes are loaded with such pieces and the motor 22 started. This causes the 75

cutter 13 to be rotated and the shafts 91 and 146 to be driven. The bucket cams 100 move with the shafts 91 to carry the respective frames 65 and 66 inwardly and outwardly alternately with respect to one another and while one frame is in presenting a piece of work to the cutter 13 the other is out in position to have its work spindles receive a piece of work as in the case of the frame 65 in Figs. 1 and 2 and the frame 66 in Figs. 2, 3 and 4.

As before stated the mechanism of the various frames operate in the same manner and when the frame 65 is in its outer position the lever 237 of its clutch is bearing on the plate 249 so that its shaft 146 is not being driven and the chuck 133 is stationary and positioned as in Fig. 1. As the cam 99 leaves the roller 219 the spring 221 acts to drive the chuck 145 against the work and cause the latter to partly enter the chuck 133. Shortly thereafter the clutch lever moves off the plate 249 so that the split ring 231 of the clutch returns to normal position due to the key 236 returning to a position square between the ends of the ring. When this occurs the clutch is again gripping the shaft 146 so that as the clutch is driven by the sprocket 148 the shaft is driven and transmits motion to the work spindles of the head and tail stocks of frame 65.

Before the clutch again grips the shaft 146 the bucket cam of frame 65 has engaged with its 30 roller to rock the frame inwardly and a new piece of work being then held by the work spindles of said frame is carried inwardly with the frame being withdrawn from the chute through the inner side thereof. This takes place against the 35 action of spring 263 and results in the finger 295 being forced outwardly by rocking of the shaft 260. Immediately the piece is removed another piece drops into its place and the spring 263 rocks the shaft 260 back to normal position causing 40 the finger 295 to engage the new piece and force it against the inwardly extending flanges of the angle bars 178 and 180 of the chute.

When the piece is removed from the chute the clutch again grips the shaft 146 as above explained so as to rotate the work spindles and the piece held by them so that said piece is rotating at high speed by the time the frame 65 is rocked inwardly a distance to bring the work against the rotary cutter. The bucket cam only moves the 50 frame inwardly so as to tilt it sufficiently to have it fall or gravitate toward the rotary cutter and does not positively feed it in the entire distance. After some material has been removed from the piece the cam 263 comes against the wear plate 55 251 and rides against it as the cam rotates with the spindle of the head stock. The cam only comes into play after most of the material to be removed has been cut away and the cam controls the finishing cut during which but a small amount 60 of material is removed giving the turned article a smoothed surface. A substantially completely turned article is shown at 255 in Fig. 4.

During the time the mechanism of frame 65 has been removing a piece from a chute the 65 mechanism of frame 66 has been presenting a piece to the rotary cutter. After the frame 65 moves inwardly the bucket cam of frame 66 cooperating with its roller starts such frame 66 outwardly. During such outward movement of a 70 frame cam 99 acts on the lever 215 of said frame to withdraw its tail stock spindle and thus release the completed piece permitting it to fall from between the work or head and tail stock spindles. If desired, any suitable chute means 75

may be provided for carrying the completed pieces into a receptacle.

While as above suggested, the inward swinging movement of a frame is not forced by the bucket cam beyond a point where the frame tends to gravitate inwardly it will be understood that the continued inward movement is controlled by the cam portion 101 so that the frame does not simply fall inwardly, jamming the work against the cutter. The cam 208 controlling the finishing cut does not engage with the wear plate 251 until after the cam portion 101 ceases to bear on its roller 111. The cam to the left in Fig. 3 is about to reach this point and when the relieved portion 105 of a cam comes opposite its roller 111, the cam will not be in engagement with its roller but the cam 208 may move against its wear plate 251 at this time controlling the last or finishing cut on the work.

From the foregoing it will be understood that it is not necessary for the operator to either position the work in the cutting spindles or to remove it from them. It is only necessary that the operator keep in the chutes a plentiful supply of pieces to be removed one at a time from the lower end thereof. The mechanisms of the respective sides of the machine present the work to the cutter preferably alternately in such timed relation that the cutter is making a roughing cut on one piece while making a finishing cut on the other and is kept busy substantially continuously with the finishing cuts. The tail stock spindle is drawn outwardly by the cam 99 rocking the lever 215 as a frame is rocked outwardly after a piece has been finished and thereby permits the piece to drop from between the work spindles and in addition locates the tail stock work spindle to be again driven forwardly to drive the next piece of work against the head stock work spindle.

With respect to the drive and the gearing disclosed it will be clear that if gear 81 is out of mesh with all of the gears 92, 93 and 94 at one side of the machine the frame at that side of the machine will not be rocked by its bucket cam and will be out of operation. Therefore, if desired, but one side of the machine may be placed in operation. The speed with which pieces of work are presented to the cutter also depends on whether the gear 81 is meshing with gear 92, 93 or 94. Attention is also directed to the fact that since the gears 81 at the respective sides of the machine are independently shiftable the timed relation between the respective sides of the machine may be adjusted to suit. That is, when one side of the machine is operating the gear 81 at the other side thereof may be shifted as desired to have the two sides of the machine work together or to have them present work to the cutter alternately or in the desired overlapping relation.

Having thus set forth the nature of my invention, what I claim is:

1. In a woodworking machine, a rotary cutter, a pivotally mounted frame at each side of said cutter, work spindles on said frames, continuously rotating cam means for moving said frames to have said work spindles present work to the cutter, each of said work spindles including a pair comprising a head and a tail stock spindle, spring means on said frames normally tending to move one spindle of a pair toward the other to grip a piece of work for presentation to the cutter, and continuously rotating cam means on said frames for moving said spindle against the action of the spring to release the work.

2. In a woodworking machine, a rotary cutter, a supply chute at each side of the cutter, work spindles at each side of the cutter, means for rotating said spindles, means for moving said spindles from the respective chutes toward the cutter to present work thereto and when the work is finished immediately move the spindles back toward the chutes, means causing the spindles to release the work as the spindles move back toward the chutes, means causing cessation of rotation of said spindles while they are at the chutes, and means operating said spindles to have them pick up a piece of work while they are at the chutes.

3. In a woodworking machine including a cutter and work spindles at each side of the cutter, a chute at each side of the cutter, means for moving said spindles to the respective chutes to take work therefrom and to move the spindles toward the cutter to present the work thereto and when the work is finished immediately move the spindles back toward the chutes; means causing the spindles to release the work as the spindles move back toward the chutes, means driving said spindles and including a clutch adapted to release on reaching a predetermined position to stop driving of and have the spindles come into required positions at the chutes during each cycle of the machine's operation.

4. In a woodworking machine including a cutter and work spindles at each side of the cutter, a chute at each side of the cutter, means for moving said spindles to the respective chutes to take work therefrom and to move the spindles toward the cutter to present the work thereto and when the work is finished immediately move the spindles back toward the chutes, means causing the spindles to release the work as the spindles move back toward the chutes means driving said spindles and including a clutch adapted to release on reaching a predetermined position to stop driving of and have the spindles come into required positions at the chutes during each cycle of the machine's operation, means to be engaged by said clutch to cause it to release, and means adjustably mounting the last means on the machine.

5. In a woodworking machine, a cutter, a pair of frames arranged one at each side of the cutter and mounted for movement toward and from the same, work spindles on each of said frames, a supply chute at each side of the cutter and from which the respective spindles are adapted to receive work, means for moving said work spindles from positions receiving work from said chutes to positions presenting the work to the cutter and when the work is finished immediately move the spindles back toward the chutes, means causing the spindles to release the work as the spindles move back toward the chutes, and adjustable stop means positively limiting movement of the frames in the direction of said chutes.

6. In a woodworking machine, a cutter, a pair of frames arranged one at each side of the cutter and mounted for movement toward and from the same, work spindles on each of said frames, a supply chute at each side of the cutter and from which the respective spindles are adapted to receive work, means for moving said work spindles from positions receiving work from said chutes to positions presenting the work to the cutter and when the work is finished immediately move the spindles back toward the chutes, means causing the spindles to release the work as the spindles move back toward the chutes, cam means

controlling the movements of said frames, and adjustable means controlling the distance the frames are moved by said cam means.

7. In a woodworking machine, a cutter, a pair of frames arranged one at each side of the cutter and mounted for movement toward and from the same, work spindles on each of said frames, a supply chute at each side of the cutter and from which the respective spindles are adapted to receive work, means for moving said work spindles from positions receiving work from said chutes to positions presenting the work to the cutter, cam means controlling movement of said frames during the roughening cut of the cutter on the work, and adapted to release the frames following said roughening cut, and profile cams on said spindles and controlling the finishing cuts on the work.

8. In a woodworking machine, a cutter, a work spindle, a supply chute, means operating said work spindle to have it take the lowermost piece of work in the chute and present it to the cutter, a rockable shaft, an arm movable by said shaft, and a spring normally tending to rock said shaft to bring said arm against the lowermost piece of work in the chute to hold it in a definite fixed position and to permit the arm to be moved as the piece of work is removed from the chute and to then cause the arm to strike the next piece of work moving into the lowermost position to force it into a definite fixed position.

9. In a woodworking machine, a cutter, a frame at each side of the cutter, a sub-table on each frame and extending along the cutter shaft, a head and a tail stock on each sub-table and each head and tail stock adapted to support a piece of work for presentation to the cutter, means to move said frames to have work presented to the cutter by the respective head and tail stocks, pivotal bearing means mounting one of said sub-tables on its frame, and means for adjusting said sub-table about its pivotal means to move one of its stocks toward and the other from the cutter for the turning of a piece having a large and a small end.

45 10. In a woodworking machine, a cutter, a pair of frames arranged one at each side of the cutter and mounted for movement toward and from the same, rotary work spindles on each of said frames, a supply chute at each side of the cutter and from which the respective work spindles are adapted to take work, cam means for moving said work spindles from positions taking work from said chutes to positions presenting the work to the cutter and controlling the positions of the work at the cutter, and means for discontinuing the operation of one of said frames at will.

11. In a woodworking machine, a cutter, a pair of frames arranged one at each side of the cutter and mounted for movement toward and from the same, work spindles on each of said frames, a supply chute at each side of the cutter and from which the respective spindles are adapted to receive work, means for moving said work spindles from positions receiving work from said chutes to positions presenting the work to the cutter, change speed gearing individual to each of said frames and controlling the rate of operation of said frames, and said change speed gearing including a gear shiftable into a neutral position to discontinue operation of one of said frames.

70 12. In a woodworking machine, a horizontal rotary shaft, a cutter on said shaft, horizontal work spindles at each side of said shaft, means for moving said spindles toward the cutter, an electric motor driving the cutter shaft, a shaft

parallel with said cutter shaft and driven therefrom, a shaft transversely of the second shaft, a worm and worm gear drive between the last mentioned shafts, a drive from said transverse shaft to said spindles, and a drive from said transverse shaft to said means for alternately moving the spindles toward the cutter.

13. In a woodworking machine, a base, a stationary upright on said base, a pair of frames pivotally mounted one at each side of the upright for swinging movement toward and from the same, cutter means on the upright, a sub-table on each frame and extending longitudinally of the cutter means, a head and a tail stock on each sub-table and each head and tail stock adapted to support a piece of work for presentation to the cutter means, means for swinging the frames toward and from the upright to have work presented to the cutter means by the respective head and tail stocks, a pivotal bearing mounting one of said sub-tables on its frame, and means for adjusting said sub-table about its pivotal bearing to move one of its stocks toward and the other from the cutter means for the turning of a piece having a large and a small end.

14. In a woodworking machine, a cutter means, a pair of frames arranged one at each side of the cutter means and mounted for movement toward and from the same, work spindles on each of said frames, means for moving said frames to have said spindles present work to the cutter means first for a roughening cut and then for a finishing cut, and means controlling movement of said frames whereby the work carried by the spindles of the respective frames is presented to the cutter means in such order that the finishing cut is being made on the work presented by one frame while the roughening cut is being made on the work presented by the other frame.

15. In a woodworking machine, cutter means, work spindles at each side of the cutter means, means for moving said spindles to and from positions presenting work to the cutter means, cam means controlling movement of said spindles during the roughening cut of the cutter means on the work and adapted to release the spindles following said roughening cut, and profile cam means controlling the finishing cuts on the work.

16. In a woodworking machine, cutter means, a pair of frames, means pivotally mounting said frames one at each side of the cutter means for movement toward and from the same, work spindles on each frame, means for rocking the frames about their pivots to carry the spindles to and from positions presenting work to the cutter means, cam means controlling movement of the frames during the roughening cut of the cutter means on the work and adapted to release the frames following said roughening cut, and profile cams controlling the finishing cuts on the work.

17. In a woodworking machine, a rotary cutter, a pivotally mounted frame at each side of the cutter, work spindles on said frames, a shaft on each of said frames, means driving said shafts, cam means on the shafts and controlling movements of the frames to have said work spindles present work to the cutter, each of said work spindles including a pair comprising a head and a tail stock spindle, a lever on each of said frames and each lever connected with a spindle of the pair on its frame, cams on said shafts and

- operable to shift said levers and the connected spindles to release a piece of work, and spring means on the frames to actuate said levers in the opposite directions to cause the spindles to grip the work.
18. In a woodworking machine, a cutter, a supply chute, a spindle operable to present work from said chute to said cutter, said chute including a work support, independent legs connected with and mounting said support, means whereby one of said legs is independently vertically adjustable to tip said support and maintain it in position with one of its ends higher than the other, a pair of side plates supported by said legs and adjustable horizontally toward and from one another and toward and from the cutter, and vertically extending guide bars on the opposing faces of said side plates and adjustably mounted for taking care of different widths of pieces to be presented to the cutter.
19. In a woodworking machine, a cutter, a supply chute, a spindle operable to present work from said chute to said cutter, said chute including a work support, independent legs connected with and mounting said support, and means whereby one of said legs is independently vertically adjustable to tip said support and maintain it in position with one of its ends higher than the other.
20. In a woodworking machine, a cutter, a supply chute, a spindle operable to present work from said chute to said cutter, said chute including a work support, a pair of legs each including a pair of sections connected by a horizontal pivot, means connecting a section of one leg with an end portion of said support, means connecting a section of the other leg with the other end portion of said support, means whereby one of said legs is independently vertically adjustable to tip said support and maintain it in position with one of its ends higher than the other, said horizontal pivots effective to permit of said adjustment, a pair of side plates supported by said legs and adjustable horizontally toward and from one another and toward and from the cutter, and vertically extending guide bars on the opposing faces of said side plates and adjustably mounted for taking care of different widths of pieces to be presented to the cutter.
21. In a woodworking machine, a base, a stationary upright on said base, a pair of frames pivotally mounted on said base one at each side of said upright for swinging movement toward and from the same, a horizontal shaft on said upright at the upper side thereof, a cutter on said shaft, means for rotating said shaft and thereby the cutter, horizontal work carrying spindles on the upper portions of said frames opposite said cutter, rollers on the upright, bucket cams on the frames and cooperating with said rollers for swinging the frames toward and from the upright to have said spindles present work to the respective sides of the cutter and controlling the positions of the work during initial cutting thereof, and means rotating said spindles while they are presenting work to the cutter.
22. In a woodworking machine, a horizontal shaft, a cutter on said shaft, means for rotating the shaft and thus the cutter, a supply chute at each side of said cutter, a frame at each side of the cutter, means pivotally mounting said frames, horizontal work spindles on each of said frames, means for rotating said spindles, cam means for rocking said frames to carry the spindles from the respective chutes toward the cutter to have the spindles present work to the cutter and controlling movements of said frames while the spindles are presenting work to the cutter and for carrying the spindles to the chutes, means causing cessation of rotation of the spindles while they are at the chutes, and means operating said spindles to have them release a finished piece of work after they have moved from the cutter and to pick up a piece of work from the chutes while they are at the chutes.
23. In a woodworking machine, a horizontal shaft, a cutter on said shaft, means for rotating the shaft and thus the cutter, a supply chute at each side of the cutter, a frame at each side of the cutter, means pivotally mounting said frames, horizontal work spindles on each of said frames, means for rotating said spindles, cam means for rocking said frames to carry the spindles from the respective chutes toward the cutter to have the spindles present work to the cutter and controlling movements of said frames while the spindles are presenting work to the cutter and for carrying the spindles to the chutes, said means for rotating the spindles including a clutch carried by the frame and adapted to release on the frame reaching a predetermined position to stop driving of and have the spindles come into required positions at the chutes during each cycle of the machine's operation, and means operating said spindles to have them release a finished piece of work after they have moved from the cutter and to pick up a piece of work from the chutes while they are at the chutes.
24. In a woodworking machine, a horizontal shaft, a cutter on said shaft, means for rotating the shaft and thus the cutter, a supply chute at each side of the cutter, a frame at each side of the cutter, means pivotally mounting said frames, horizontal work spindles on each of said frames, means for rotating said spindles, cam means for rocking said frames to carry the spindles from the respective chutes toward the cutter to have the spindles present work to the cutter and controlling movements of said frames while the spindles are presenting work to the cutter and for carrying the spindles to the chutes, said means for rotating the spindles including a clutch carried by the frame and adapted to release on the frame reaching a predetermined position to stop driving of and have the spindles come into required positions at the chutes during each cycle of the machine's operation, and means to be engaged by said clutch to cause it to release, means adjustably mounting the last means on the machine, and means operating said spindles to have them release a finished piece of work after they have moved from the cutter and to pick up a piece of work from the chutes while they are at the chutes.
25. In a woodworking machine, a horizontal shaft, a cutter on said shaft, means for rotating the shaft and thus the cutter, a supply chute at each side of said cutter, a frame at each side of the cutter, means pivotally mounting said frames, horizontal work spindles on each of said frames, means for rotating said spindles, means for rocking said frames to move said spindles from positions receiving work from said chutes to positions presenting the work to the respective sides of the cutter, cams controlling movements of the frames toward and from the cutter and while the spindles are presenting work to the cutter, and adjustable means controlling the distances the frames are moved by said cam means.
26. In a woodworking machine, a horizontal

shaft, a cutter on said shaft, means for rotating the shaft and thus the cutter, a supply chute at each side of said cutter, a frame at each side of the cutter, means pivotally mounting said frames, horizontal work spindles on each of said frames, means for rotating said spindles, and cam means for rocking said frames about their respective pivotal mountings to carry the spindles into and out of positions presenting work to the respective sides of the cutter and controlling movements of said frames while the spindles are presenting work to the cutter.

27. In a woodworking machine, a cutter, a

work spindle, a supply chute including a back, means operating said work spindle to have it take the lowermost piece of work from the chute through the front side thereof and present it to the cutter, an arm, a spring connected with said arm, means whereby as the lowermost piece is removed from the chute the spring is loaded, and said spring then operable to cause said arm to strike the next piece of work moving into the lowermost position in the chute and force such piece into position against the back of the chute. 5 10

IVAN H. BRADLEY.
